UNITED STATES PATENT OFFICE.

BERENT MARTIN, OF SAN FRANCISCO, CALIFORNIA.

DESIGN FOR A DOORKNOB.

Application filed April 15, 1924. Serial No. 9,284. Term of patent 3½ years.

To all whom it may concern:

Be it known that I, BERENT MARTIN, a citizen of the United States, residing at 13 Porter Street, in the city and county of San Francisco, State of California, have invented a new, original, and ornamental Design for a Doorknob, of which the following is a specification, reference being had to the accompanying drawing, forming part thereof.

Fig. 1 is a side elevation; and Fig. 2 is a front elevation of a doorknob, showing my new design.

I claim:

The ornamental design for a doorknob, as shown.

BERENT MARTIN.
